US0D1106095S

(12) **United States Design Patent** (10) Patent No.: **US D1,106,095 S**
(45) Date of Patent: ** Dec. 16, 2025

(54) **INTERACTIVE SMARTBOARD**

(71) Applicants: **Guangzhou Shiyuan Electronic Technology Company Limited, Guangdong (CN); GUANGZHOU SHIZHEN INFORMATION TECHNOLOGY CO., LTD., Guangdong (CN)**

(72) Inventor: **Fanglong Hu, Guangdong (CN)**

(73) Assignees: **Guangzhou Shiyuan Electronic Technology Company Limited, Guangdong (CN); Guangzhou Shizhen Information Technology Co., LTD., Guangdong (CN)**

(**) Term: **15 Years**

(21) Appl. No.: **29/948,994**

(22) Filed: **Jun. 25, 2024**

Related U.S. Application Data

(62) Division of application No. 29/730,997, filed on Apr. 10, 2020, now Pat. No. Des. 1,037,191.

(30) **Foreign Application Priority Data**

Oct. 11, 2019 (CN) 201930553992.4

(51) **LOC (15) Cl.** **14-03**

(52) **U.S. Cl.**

USPC **D14/125**

(58) **Field of Classification Search**

USPC D14/126, 125, 128, 129, 336, 335, 337, D14/371, 496

CPC .. H04N 7/00; H04N 5/64; H04N 7/14; H04N 5/44; G09F 1/12; G09F 1/00

See application file for complete search history.

(57) **CLAIM**

The ornamental design for an interactive smartboard as shown and described.

DESCRIPTION

FIG. 1 is a front view of an interactive smartboard showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a front perspective view thereof.

Broken lines illustrate portions of the interactive smartboard that form no part of the claimed design.

1 Claim, 7 Drawing Sheets
